CLOSURE APPLYING APPARATUS

Charles F. Schmidt, Toledo, Ohio, assignor to
Owens-Illinois Glass Company, a corporation
of Ohio

Application September 30, 1937, Serial No. 166,669

2 Claims. (Cl. 226—87)

The present invention relates to improvements in apparatus for applying metal closures to bottle necks, jugs, jars, and like receptacles by a spinning process in which the lower marginal regions of the depending attaching skirt are spun beneath an external bead or flange provided on the neck of the receptacle.

The principal object of the invention is to provide a closure applying apparatus which is relatively simple in its construction and which therefore may be manufactured at low cost; one which is simple in its operation and which therefore does not require the services of a skilled operator; one which is rugged and durable and which therefore is unlikely to get out of order; and one which will effectively, dependably and uniformly apply the closures to the receptacles.

Another object of the invention is to provide an apparatus for applying closures to receptacles which will operate efficiently regardless of any irregularities that may occur on the bottle necks or regardless of the fact that occasionally some of the bottle necks may be slightly out-of-round.

Other objects of the invention, not at this time enumerated, will become apparent hereinafter.

In the accompanying drawings:

Fig. 1 is a vertical sectional view taken centrally through an apparatus constructed in accordance with the principles of the present invention and showing the same operatively associated with a jug to which a closure is to be applied;

Fig. 2 is a sectional view taken substantially along the line 2—2 of Fig. 1;

Fig. 3 is a sectional view similar to Fig. 2 with the parts thereof in operative spinning position;

Fig. 4 is a sectional view taken substantially along the line 4—4 of Fig. 1;

Fig. 5 is a vertical sectional view taken centrally through the apparatus at right angles to the section plane of Fig. 1 with the parts thereof in operative spinning relation;

Fig. 6 is a sectional view taken substantially along the line 6—6 of Fig. 4;

Fig. 7 is a sectional view taken substantially along the line 7—7 of Fig. 6;

Fig. 8 is a sectional view taken substantially along the line 8—8 of Fig. 7;

Fig. 9 is a sectional view taken substantially along the line 9—9 of Fig. 1; and

Fig. 10 is a fragmentary side elevational view, diagrammatic in its representation, of the closure applying apparatus showing the same operatively associated with a conventional type of drill press.

Referring particularly to Figs. 1, 5 and 10, a receptacle in the form of a jug J having an en-

larged reinforcing bead 10 providing a shoulder 11 at its neck portion is adapted to have a closure C applied thereto, in the relation shown particularly in Fig. 5. That is, by the means hereinafter described, the closure C, being previously placed over the mouth of the jug J, is forced downwardly against the rim of the jug while the lower edge of the closure skirt is spun inwardly beneath the shoulder 11 to retain the closure C on the jug.

The apparatus involves in its general organization a cylindrical casing 12 (Figs. 1 and 5) which is open at its lower end and which is provided at its upper end with a boss 13 provided with a socket 14 therein designed to receive the lower end of a spindle 15 which is carried by 10 the chuck 16 of a rotary press P which may, for example, be a conventional type of drill press having a support S for the jug J. An apron 17 which is somewhat of a bell-shape design and having slots 24 therein is secured to and suspended from the lower open end of the casing 12 and extends downwardly to enclose the operative spinning instrumentalities of the apparatus.

The cylindrical casing 12 provides a cylinder 18 in which there is slidably mounted a two-part 25 hollow inner casing consisting of a casing proper 19 and a closure 21 for the upper end thereof which is secured thereto by means of securing screws 22. Lugs 20 (Fig. 9) extending upwardly from the closure 21 slidably extend between lugs 30 30 formed on the casing 12 to prevent relative turning movement between the casing 19, 21 and the casing 12. The casing 19, 21 provides a chamber 23 in which are housed the operating instrumentalities for the spinning mechanism 35 now to be described.

The spinning mechanism just referred to consists of a plurality of spinning disks D (Figs. 5 and 6) which are supported at the lower ends of respective depending supports or carriers 25. 40 The supports 25 are mounted for swinging movement toward and away from the neck of the jug J about the axes of respective shafts 26. The shafts 26 extend into the casing 19 through bosses 27 and carry at their upper ends respective torque applying members 28 which constitute elements of the operating instrumentalities for the spinning mechanism. The supports 25 are eccentrically mounted on the shafts 26 by means of split clamping arms 29 (see also Fig. 2) 50 and are clamped thereto by means of clamping bolts 31.

Each support 25 comprises a casting 32 (Fig. 7) having a slideway 33 formed therein which is slidably disposed a slide member 34 provided with 55

a depending boss 35. The spinning disk D is rotatably mounted on the boss 35 and is retained thereon by means of a cap screw 36. An oil passage 37 extends through the casting 32 and 5 slide member 34 to a point adjacent the disk D. The slide member 34 is normally maintained in the extended position illustrated in Fig. 7 by means of a coil spring 38, and a tie rod 39 extending through the member 34 and casting 32 10 determines the limiting position of the former. An adjusting nut 41 and lock nut 42 permit the tension of the coil spring 38 to be adjusted in order that the proper flanging pressure of the disk D against the neck of the jug J may be 15 attained. It will be seen that when the disk D is in spinning contact with the skirt of the closure C on the jug J, any irregularities in the contour of the bottle neck or any out-of-roundness thereof will be automatically compensated for inasmuch 20 as the slide member 34 will yield in the slide-way 33.

Referring now to Figs. 1 and 5, the operating instrumentalities for the spinning disks D include the torque applying members 28, which are 25 mounted on their respective shafts 26, and which are in the form of castings in which rollers 43, eccentrically disposed with respect to the shafts 26, are rotatably supported. Compression springs 44 anchored on the casing 19 bear against the 30 members 28 and normally urge the same inwardly of the casing, thus applying torque to the shafts 26 in order to swing the supports 25 and disks D carried thereby outwardly to inoperative positions. The slots 24 in the apron 17 provide a clearance 35 for the supports 25 in their inoperative positions.

In order to hold the closure C firmly upon the jug J during the spinning operation, a pressure 40 chuck 45 having a recess 46 therein designed to fit over the top of the closure C and provided with an internal shoulder 47 adapted to bear 45 downwardly against the periphery of the closure top is rotatably suspended from the lower end of a shaft 48 and is retained thereon by means 50 of a cap screw 49. An anti-friction thrust bearing 51 occupies a position between the chuck 45 and a pressure plate 52 secured to the shaft 48. The upper end of the shaft 48 is threadedly received in an internal boss 53 formed on the casing 19 and a spanner nut 54 serves to retain the shaft therein in any desired position of adjustment.

A hollow expansion plunger 55 is provided on 55 its lower end with a downwardly directed inwardly tapering cam surface 55* which is adapted to operatively engage the torque applying members 28 and move them outwardly. The plunger is telescoped over the boss 53 and is normally maintained in elevated position by means of a 60 compression spring 56 disposed within the same. The upper end of the plunger 55 is centered in the casing 12 by means of an extension or centering pin 57 which extends through a bushing 58 provided on the boss 13. An anti-friction thrust 65 bearing 59 is centered on the pin 57 and is disposed between the casing 12 and the plunger 55. A compression spring 60 surrounds the plunger 55 and operates to normally maintain the inner casing 19, 21 extended from the cylinder 18. Additional compression springs 61 mounted on tie rods 62 aid in maintaining the inner casing 19, 21 70 extended from the cylinder 18, while adjusting nuts 63 threadedly received on the tie rods 62 adjustably limit the extent to which the casing 19, 75 21 may be extended from the cylinder 18. A pair

of abutments 64 carried by the casing closure 21 are adapted to engage the lower ends of a pair of limit stops 65 which are in the form of adjusting bolts that extend through the casing 12.

In the application of the closures C to the jug J, a jug is positioned beneath the apparatus on the support 8 and a cap is placed over the filling opening thereof. The operator of the apparatus depresses the usual operating lever of the drill press and lowers the chuck 16, together with the 10 entire rotating apparatus. The holding chuck 45 engages the closure C. By virtue of the anti-friction thrust bearing 51, the frictional engagement of the chuck 45 with the closure C causes the former to come to rest while the remainder of 15 the apparatus continues to rotate. The compression springs 56, 60, and 61 yield simultaneously and the casing 19, 21 moves into the cylinder 18 which descends thereon. Upon descent of the casing 12 and apron 17, the plunger 55 moves 20 downwardly on the boss 53 and the cam 55* engages the rollers 43, thus moving the torque applying members 28 (Fig. 4) outwardly against the compression of the springs 44. Torque is applied to the shafts 26 and thus the supports 25 and 25 disks D carried thereby are moved inwardly so that the disks D engage the lower marginal region of the closure C to spin the same underneath the shoulder 11 provided by the bead 10 on the neck of the jug J. Upon raising of the chuck 16, the 30 various instrumentalities are returned to their normal inoperative positions by virtue of the compression springs 56, 60, and 61.

It is to be noted that should the neck of the jug J be slightly out-of-round, or should any irregularities occur therein, the slide member 34 will yield. By means of the adjusting nut 41, the operator may adjust the tension of the spring 38 so that the disks D will properly follow the contour of the neck of the jug J.

Modifications may be resorted to within the spirit of the appended claims.

I claim:

1. A closure applying apparatus comprising a casing providing a cylinder, a second casing slidably disposed within said cylinder and extensible therefrom, means normally maintaining said second casing extended from the cylinder, a chuck carried by said second casing and movable therewith, a shaft extending through said second casing eccentrically of the chuck, spinning means carried by said shaft eccentrically thereof and movable toward and away from said chuck upon turning of said shaft, a torque applying member mounted on said shaft within the second casing, a plunger connected to said first mentioned casing for movement therewith relative to the second casing and extending into said latter casing, said plunger having a cam surface thereon designed for camming engagement with said torque applying member, and means for rotating said first mentioned casing.

2. A closure applying apparatus comprising a supporting casing providing a cylinder, a second casing slidably disposed within said cylinder and extensible therefrom, means normally maintaining said second casing extended from the cylinder, means for retaining said casing against relative rotation, a chuck carried by said second casing and movable therewith for holding a skirted closure against relative movement on a bottle neck, a shaft extending through said second casing eccentrically of the chuck, spinning means yieldably carried by said shaft eccentrically thereof and movable in a horizontal plane toward and 75

away from operative engagement with said closure and bottle upon turning of said shaft, a torque applying member mounted on said shaft within the second casing, a plunger connected to said first mentioned casing for movement therewith relative to the second casing and extending into said latter casing, said plunger hav-

ing a cam surface thereon designed for camming engagement with said torque applying member, means for imparting vertical and rotary movement to said first mentioned casing, and a hood attached to said casing and enclosing said spinning means. 5
